ATTORNEY

UNITED STATES PATENT OFFICE.

CHARLES F. BONHACK, OF NEW YORK, N. Y.

MACHINE FOR SETTING MATCH-STICKS.

SPECIFICATION forming part of Letters Patent No. 254,192, dated February 28, 1882.

Application filed December 12, 1881. (No model.)

To all whom it may concern:

Be it known that I, CHARLES F. BONHACK, of the city, county, and State of New York, have invented certain new and useful Improvements in Machines for Setting Match-Sticks, of which the following is a specification.

This invention has reference to an improved machine to be used in the manufacture of friction-matches, it being designed with a special view for simplifying and expediting the setting of the sticks into position ready to be dipped and dried, the apparatus being based on the principle of making matches from single sticks instead of from double sticks, as has been heretofore the case.

The invention consists of a fixed grating at the bottom of the apparatus, and of a movable setter having a series of equidistant push-pins which are forced by suitable mechanism through a compact bunch of sticks held together by a strong rubber band, the bunch of sticks being retained in position intermediately between the grating and the setter by suitable retaining devices, so that the push-pins of the setter can be forced through the bunch up to a perforated guide-board. The setter is applied in a detachable manner to a follower which is moved by any suitable mechanism.

In the accompanying drawings, Figure 1 represents a front elevation, partly in section, of my improved machine for setting the sticks of friction-matches. Fig. 2 is a vertical transverse section of the same. Figs. 3 and 4 are perspective views of a bunch of sticks, shown respectively before and after setting, and Figs. 5 and 6 are detail views respectively of the perforated guide-board of the setter and of the fixed grating.

Similar letters of reference indicate corresponding parts.

A in the drawings represents the supporting-frame of my improved machine for setting match-sticks, which consists of a bed-plate, *a*, upright supporting-pillars *b*, and a top piece, *d*, connecting the pillars. The pillars guide the follower *B*, that is lowered by means of a screw, lever, or other suitable mechanism.

On the bed-plate *a* is supported, at some distance above the same, a fixed wire grating, *C*, the intersecting wires of which are placed at such a distance from each other as to leave

square intermediate spaces of sufficient width to admit one stick to pass through each space, while the grating prevents the remaining sticks of the bunch from changing their position.

Upon the grating *C* is supported a closely-packed bunch, *D*, of match-sticks, the latter being of the length of a single match and firmly held in position by means of a strong rubber band, *D'*, which is of suitable width and thickness for this purpose. The bunch *D* is retained in position on the grating *C* by means of locking slide-straps *E*, which are pivoted to a fixed side piece, *E'*, of frame *A* and locked by suitable fastening devices at their opposite ends to a side piece, *E''*, that is hinged at its lower ends to the bed-plate *a*, so that when the retaining-straps *E* are thrown up the hinged side piece, *E''*, may be thrown down and the bunch be conveniently placed in position on or removed from the grating.

Into the dovetailed under side of the follower *B* is inserted the stick-setter *F* by means of a dovetailed center portion, as shown in Fig. 1, the setter *F* consisting of a top board to which as many push-pins *f* are applied as there are spaces formed by the wires of the grating *C*, the push-pins being arranged equidistantly from each other and in rows, and in such a manner as to be vertically above and in line with the centers of the intermediate spaces formed by the wires of the grating when the setter is inserted in the proper position into the follower. Below the top piece of the setter is arranged a perforated guide-board, *F'*, through which the pins pass, so as to project a certain distance below the same. The setter *F* is arranged at opposite sides with side pieces, *F''*, which are made tapering at the ends, so as to fit into grooves at the top of the guide-board *F'*, said side pieces being hinged to the top piece of the setter *F*, so as to be capable of being released from the guide-board, and being thrown up alongside of the top piece of the setter whenever at the proper stage in the manufacture of the matches the sticks have to be forced entirely out of the bunch. The setter *F* is removed, together with the bunch, from the follower of the machine after the sticks have been set by the push-pins. The setter is retained on the bunch during the dipping operation, so as not to disturb the position of the push-pins.

in the bunch. The setter is adapted to be inserted bodily with the bunch of sticks into a machine for unloading matches after the protruding sticks have been dipped, said machine having a follower of the same size and construction as the follower of the stick-setting machine, as will appear more fully in a separate application for a machine for unloading matches filed at the same time herewith.

10 The apparatus is operated as follows: The bunch is placed on the grating and locked in position thereon by the side straps. The setter is then placed in position in the follower, its guide-board being held by the hinged side pieces. The setter is then lowered by means of the operating mechanism of the follower, so that the ends of the push-pins *f* press down upon the bunch, pushing forward as many individual sticks as there are pins in the setter, and forcing them down through the spaces of the grating into the space below the same, as shown clearly in Fig. 2. The setter is then removed from the apparatus by releasing the locking device of the bunch and lowering the 25 side piece *E*², the bunch having then a number of sticks projecting therefrom, as shown clearly in Fig. 4. The entire setter, together with the bunch of sticks, is now removed and the sticks dipped successively into the different substances by which the match-heads are formed, the matches being then allowed to dry 30 while remaining in the setter. When they are dry the setter is placed in an unloading apparatus, by which they are forced out entirely of the bunch by the push-pins, after releasing the hinged side pieces of the top piece from the 35 guide-board of the setter.

The advantages of my improved match-stick-setting machine are, first, that the same bunch 40 may be used three or four times in succession for setting match-sticks therefrom, as the retaining-band holds the sticks reliably in position for the action of the push-pins; secondly,

that the setting is accomplished in a much quicker manner than by the setting-machines now in use; thirdly, that by the setting mechanism the manufacture of single matches may be successfully accomplished, as contradistinguished from the methods of making them in double sticks, and finally separating the sticks by means of circular saws, which causes considerable loss, and frequently accidents to the girls handling the matches; and lastly, that a fixed number of matches—say one hundred—may be arranged in one row by the setting-machine and unloaded by the unloading-machine, so as to be packed directly in equal quantities for shipment.

Having thus described my invention, I claim as new and desire to secure by Letters Patent—

1. A match-stick-setting machine consisting of a fixed wire grating, *C*, with means for locking the bunch of sticks to the grating, of a movable and detachable setter having a series of equidistant push-pins and a perforated guide-board, and means for operating the setter, all substantially as and for the purpose set forth.

2. The combination, in a match-stick-setting machine, of a fixed grating, *C*, with locking side straps, *E*, pivoted to a fixed side piece, *E*¹, and locked to a hinged side piece, *E*², at the opposite side for retaining the bunch of match-sticks in position on the grating, substantially as set forth.

3. In a match-stick-setting machine, a stick-setter, *F*, consisting of a top piece having equidistant push-pins *f*, an adjustable perforated guide-board *F*¹, and hinged side pieces, *E*², substantially as and for the purpose described.

In testimony that I claim the foregoing as my invention I have signed my name in presence of two subscribing witnesses.

CHARLES F. BONHACK.
